INVENTOR

ARETE C. BISHOP

BY

W. H. Emissor
REG. ATTORNEY

UNITED STATES PATENT OFFICE.

ARETE C. BISHOP, OF NEW YORK, N. Y.

TYPE CLEANER.

Application filed January 13, 1923. Serial No. 612,515.

To all whom it may concern:

Be it known that I, ARETE C. BISHOP, a citizen of the United States, residing in the city, county, and State of New York, have 5 invented new and useful Improvements in Type Cleaners, of which the following is a specification.

This invention relates to type cleaning attachments for typewriters, and is in the nature of an improvement over the attachment shown and claimed in my prior Patent No. 955,939, granted April 26, 1910.

An object of this invention is to provide an improved, simplified, less expensive, less cumbersome, more durable, and more easily operated cleaning attachment, which can be made largely from stock and standard materials, and from stamped and formed sheet metal, and which is exceptionally simple and 20 light in weight. Other objects and advantages will be apparent from the following description of an embodiment of the invention and the novel features will be particularly pointed out in claims.

25 In the accompanying drawings:

Fig. 1 is a front elevation of a portion of a typewriter with one form of my improved attachment thereon, and

Fig. 2 is a plan of the same.

30 In the illustrated embodiment, a pair of angular plates 1 and 2 of sheet metal are attached to the frame 3 of a typewriter, by passing the screws 4 that form part of the frame through the angular extending arms 35 5 and 6 of each plate, so as to clamp the plates to the frame upon the upper face thereof and adjacent the forward edge. The arms 6 are preferably bent at their free ends so as to extend over the corner 40 edge of the frame and assist in holding the plates against displacement. The plates are disposed upon the frame, one at each side of the usual group of type 7 that are carried upon the free ends of the usual pivoted type arms 8.

The inner edges of the plates 1 and 2 are rolled upon themselves to form upon each a cylindrical sleeve or bearing 9 which extends forwardly and rearwardly of the frame 3. A rod 10 is slidably disposed in each sleeve or bearing 9 and each carries at its inner end a transversely extending cotter pin 11 which limits its forward movement in the bearing or sleeve.

55 A plate 12 is secured by screws 13 across the forward ends of the rods 10 so as to

cause movement of the rods 10 in unison. A helical spring 14 surrounds each rod 10 between its sleeve or bearing and the plate, and by pressing upon the bearings and 60 plates, these springs serve to press the plate 12 and rods forwardly as far as permitted by the cotter pins 11. A bar 15 carrying bristles 16 extending from its lower face is clamped to the inner face of the plate 12 in 65 a suitable manner such as by double angle strips 17 which at one end overlie the bar 15 and at the other end are clamped to the plate 12 by screws 18 that pass through the plate 12 and have threaded engagement with 70 the angle strips. In the illustrated model of typewriter, the type are arranged arcuately and consequently the bar 15 for this model will also be arcuate with an approximately corresponding center of curvature. 75 When the rods 10 are at their forward limit of movement the bar 15 and bristles 16 will be disposed forwardly of and clear of the type 7, so as to permit of the normal and uninterrupted movements of the type to 80 ward and from the platen. When the plate 12 is pushed rearwardly, the bristles 16 will be carried across and in contact with the faces of the type so as to brush the same and thereby remove therefrom any accumulation 85 of dust, thickened ink, lint, etc. When the plate is released, the springs 14 will act and shift the plate and bristles forwardly to their inactive or normal position. The plate 12 and bar brush 15 together constitute what 90 I may hereafter refer to as a brush device.

In the use of the attachment it will be applied to the frame of a typewriter in the manner indicated, and will normally be inactive. When one desires to clean the type 95 it is merely necessary to push the plate 12 rearwardly and release it, a few times, which will cause corresponding movements of the bristles across the faces of the type to clean the same. This cleaning operation re- 100 quires but a few moments of time and the attachment is always ready for use instantly. The plates 1 and 2, the plate 12, and the angle strips 17 can be made from stamped sheet metal by suitable dies in an inexpensive manner, the rods 10 are standard rods, and the springs and cotter pins are stock material that may be purchased almost anywhere.

105 It will be obvious that various changes in 110 the details and arrangements of parts, herein described and illustrated for the purpose

of explaining the nature of the invention, may be made by those skilled in the art, within the principle and scope of the invention.

5 I claim:

1. A type cleaning attachment for typewriters comprising supporting members adapted to be secured to the frame of the typewriter at opposite sides of the group of 10 type and having bearing apertures extending forwardly and rearwardly of the typewriter, a rod slidable endwise in each of said bearing apertures, a brush device connected between the rods and carrying bristles which move across and in contact with the face of the type when the rods and brush device are reciprocated from front to rear, springs surrounding the rods and pressing them and the brush device to one 15 position in which the bristles are clear of the type, and means for limiting the movement of the rods and brush device beyond said one position.

2. A type cleaning attachment for typewriters comprising a brush device carrying bristles thereon, parallel rods extending from one face of the device, bearing elements arranged on the frame of the typewriter and in which the device reciprocates 20 from front to rear of the typewriter so as to carry the bristles across and in contact with the face of the type, means for limiting the forward movement of the device to a position in which the brush device clears 25 the type in their printing movements, and spring means on the rods and acting against the bearing elements for pressing the device to its forward position.

3. A type cleaning attachment for typewriters comprising a brush device carrying bristles thereon, parallel rods extending from one face of the device, bearing elements arranged on the frame of the typewriter and in which the device reciprocates 30 from front to rear of the typewriter so as to carry the bristles across and in contact with the face of the type, pins carried by the rods and co-acting with the bearing elements to limit the forward movement of the 35 device to a position in which the brush device clears the type in their printing movements, and spring means on the rods and acting against the bearing elements for pressing the device to its forward position.

4. A type cleaning attachment for typewriters comprising a brush device carrying bristles thereon, parallel rods extending from one face of the device, bearing elements arranged on the frame of the typewriter and in which the device reciprocates 40

from front to rear of the typewriter so as to carry the bristles across and in contact with the face of the type, pins carried by the rods and co-acting with the bearing elements to limit the forward movement of the 45 device to a position in which the brush device clears the type in their printing movements, and helical springs surrounding the rods and pressing them to their forward positions determined by the pins. 70

5. A type cleaning attachment for typewriters comprising a frame mounted for movement forwardly and rearwardly across and in proximity to the type, a brush, and clamping means, including angle members 75 secured to and overlying the brush for securing it to the frame with the bristles in a position to contact with and clean the type as the frame moves forwardly and rearwardly. 80

6. A type cleaning attachment for typewriters comprising plates of sheet metal adapted for attachment to the frame of the typewriter at opposite sides of the group of 85 type and having their inner edges rolled thereon to provide cylindrical bearings extending in directions forwardly and rearwardly of the typewriter, rods slidable in said bearings, means for limiting the forward movement of the rods, helical springs 90 surrounding the rods and pressing them forwardly to the extent permitted by the limiting means, and a brush device carried by the rods so as to clear the type when in its forward position and move across and in contact with the type when shifted rearwardly against the action of the springs. 95

7. A type cleaning attachment for typewriters comprising plates of sheet metal adapted for attachment to the frame of the 100 typewriter at opposite sides of the group of type and having their inner edges rolled thereon to provide cylindrical bearings extending in directions forwardly and rearwardly of the typewriter, rods slidable in said bearings, a pin carried by each rod adjacent its rear end and engaging with the plates to limit forward movement of the rods, helical springs surrounding the rods 105 and pressing them forwardly to the extent permitted by the limiting means, and a brush device carried by the rods so as to clear the type when in its forward position and move across and in contact with the type when shifted rearwardly against the action 110 of the springs. 115

In testimony whereof I have hereunto set my hand.

ARETE C. BISHOP.
